BEATING AND REFINING ENGINE.

1,122,682.

Specification of Letters Patent.

Patented Dec. 29, 1914.

Application filed January 21, 1913. Serial No. 743,272.

To all whom it may concern:

Be it known that I, EDWARD P. BUTTS, a citizen of the United States of America, residing at Springfield, in the county of 5 Hampden and State of Massachusetts, have invented new and useful Improvements in Beating and Refining Engines, of which the following is a specification.

This invention relates to paper making 10 and has special reference to beating and refining engines of that type known in the trade as "Jordan" engines,—the object of the invention being to provide an improved engine of this type so constructed and arranged as to do away with the heavy end-thrust to which the shaft of such engines is subjected when the machine is in operation, which thrust is due to the conical shape of the principal parts of the machine.

20 A second and very important object of the invention lies in the combination of two of these engines in such operative relation, one to the other, as will eliminate the end-thrust on the shaft as described above, and 25 in making the cone of one of the engines of greater area than the other, the cones of the two engines being fixed to the same shaft, the latter being permitted to move endwise within narrow limits, and the conical casings of the cones being adjustable in 30 the direction of their axes, the two casings being so provided with conduits in this particular combination that pulp fed into one engine will pass from the outlet end thereof 35 to the inlet end of the other and through the latter. By means of this construction and arrangement of the two engine units, a setting or adjustment is made possible (and this is a feature which applicant con-

40 siders new in this art) whereby different counter-acting pressures in the casings of the two engines are made available, which, acting on the cones of different areas, will effect the endwise positioning of the shaft 45 and cones automatically, to the end that the setting or adjustment of one cone relative to its casing will be closer than the setting of the other cone,—the shaft "floating" as it may be termed, but maintained by the counter-acting pressures in a substantially fixed 50 plane of rotation. The reason why the cone having the greater area can not move the smaller cone far enough to cause the knives thereon to come into contact with the knives 55 of the casing is that a cushion of pulp is always present between the surface of the

cone and the wall of the casing which is always maintained by the pressure in the supply-pipe, and, as the smaller cone is brought into nearer relation to its casing, 60 this cushion of pulp is compacted, thus ultimately establishing a pressure which counter-balances the opposing pressure of the cone having the greater area. Furthermore, simultaneously with the increase of resistance to compression of the pulp cushion surrounding the smaller cone, the pressure on the pulp cushion surrounding the cone having the larger area decreases, owing to the movement of the latter cone away from 70 its casing. Hence, by a suitable adjustment of the casings of the two cones any desired degree of refining action in the two engines may be attained, but the refining action will be less in the engine having the 75 larger cone, and thus pulp passing from the latter to the other engine will be subjected to two refining reductions of increasing fineness, the degree of reduction in the two engines being inversely proportionate 80 to the respective areas of the two cones. That is to say, by reason of the fact that one engine has a larger grinding surface, the pressure per unit area will be less on this cylinder than in the smaller engine. In 85 the present stage of pulp refining, it is desired that the first treatment of pulp shall be less harsh than the second, in order to obtain a better grade of paper, and, for this reason the grinding area of the first 90 engine is made larger than the second engine. It is also clear that by reason of the adjustments of the casings any desired refinement of the product desired can be obtained.

95 While from the point of view of mechanical efficiency and convenience, it is desirable that the two casings should be adjusted simultaneously, each may be made independently adjustable, if desired, in the manner well 100 understood in this art.

The invention is clearly shown in the accompanying drawings, in which,—

Figure 1 is a side elevation of a machine embodying the invention, certain 105 parts being in section. This view shows the two engine units arranged in their operative relation with means for simultaneous adjustment of the two casings,—toward and from each other,—and it shows, further, the type of machine in which the cone of one unit is of greater area than

that of the other. Fig. 2 is a sectional view through the machine on line 2—2, showing the manner of mounting the movable casings of the engines on the base to permit 5 of their adjustment in the direction of the axes of the cones.

Referring to the drawings in detail,—*a* indicates the base of the machine, provided with suitable standards *b* in which the 10 shaft *c* is mounted, this being the main shaft of the machine and having secured to it the cones *d* of the two engine units. These cones are, as shown in the drawings, 15 fixed on the shaft *c* in opposed relation, and between the two central standards *b* a driving pulley *e* is mounted on the shaft, whereby the two cones may be rotated. As usual 20 in this type of refining engine, the cones are inclosed in conical casings *f*, these casings each being provided with a base or standard *g*, the lower portion of which is flanged, as shown in Fig. 3, at *h*, and fitted 25 into a groove formed in the base, the standards being locked in said groove by means of the overhanging lips *k* and the bolts *m*.

An attaching shaft for the two casings *f* is mounted in the two central standards *b*, *b*, to rotate in a fixed plane, the shaft being indicated by *o*. The opposite ends of 30 this shaft are provided with right and left-hand threads, which enter suitably threaded holes of the standard *g*,—lock-nuts *p* being provided to screw up against the standards and lock the shaft thereto. Any suitable 35 means may be provided for rotating the shaft *o*, as, for example, the collar *q* having spanner-holes *r* therein. The cones and casings of the two engine units are built in the manner customary in the ordinary 40 type of refining engine, being provided with the knives *s* fixed on the cone and the knives *t* fixed on the interior wall of the casing, the contiguous edges of these knives being parallel. The term "knives" is used 45 herein in a generic sense. Any other reducing element may be used in place of the knives. On the opposite ends of the shaft *c* are provided adjusting-nuts *v* which are adapted to screw up against the outer ends 50 of the shaft-bearings in these standards.

As described above, the two cones in the machine shown in Fig. 1, have different areas,—that on the right-hand end of the machine having a greater area than that 55 on the left. The unit on the right of the machine,—that is, the one having the greater area,—is the one into which the pulp is first introduced from a suitable source of supply through the pipe *w* which, 60 as is customary, enters the casing near the apex of the cone. From the lower rear end of this casing *f*, a pipe *x* extends to the casing of the cone on the left-hand end of the machine and enters the latter near the 65 apex of the cone therein, the exit from the

casing being by the pipe *y* located at the lower part of the rear end thereof.

As already described, when the pulp enters the casing *f* of the unit at the left-hand side of the machine, it is under a certain 70 definite head or pressure, and the entire casing will, as the machine continues to run, be filled with pulp; that is to say, the annular space between the cone and the casing will be so filled. The pulp, as it works 75 through from the apex toward the base of the cone will be refined, and from this cone passing through the pipe *x* to the other cone, where the same operation takes place. When the machine is started, the two nuts *v* on opposite ends of the shaft *c* are backed off more or less, thus permitting the shaft *c* to have a certain degree of endwise play within its 80 bearings; consequently, as the two cones are located on the shaft in opposed relation, the 85 endwise thrust of one is counteracted by the like endwise thrust of the other, and as the cone in the right-hand end, as shown in the drawing, has the larger area, the thrust of this cone will be in excess of the counteracting 90 thrust of the cone in the left-hand end. Therefore, the shaft *c* having more or less 95 endwise movement in its bearings, the excess of thrust developed in the right-hand cone will draw the left-hand cone into its casing 100 as the first-named cone tends to move in the opposite direction. This, however, results in a compression of the body of the pulp located between the surface of the cone and its inclosing casing, and this increased compression results in eventually establishing a 105 resistance to further movement of the left-hand cone, due to the equalization of the pressures in the two units. The relative setting, therefore, of the two cones becomes 110 automatically established, and the pulp passing from this unit to the one on the left, (in which the separation 115 of the edges of the knives is less than that in the first-named unit,) the pulp receives a greater degree or harder treatment of refining than in said first named unit owing to the smaller area of this cone, it being thus subjected to two successive refining operations.

To vary the setting of the two cones, the casings *f* may be adjusted one toward the 120 other, or one away from the other, simultaneously, by means of the screw-shaft *o*; or if desired, cones may be provided for adjusting these casings independently, as 125 stated.

It is quite obvious that if the two cones were fixed on the shaft with their bases in contiguous relation instead of as shown and described herein, the same counterbalancing of the end-thrust would be effected, and in 130

either case the two cones would be, as it were, in opposition, and where this word is used in the claims it is intended to refer to the arrangement of the cones on the shaft, either 5 with their bases or their apices in contiguous relation.

What I claim, is,—

1. An engine of the type described for refining pulp comprising a shaft, two conical 10 members fixed thereon with their apices in contiguous relation one to the other, one of said members having a greater superficial area than the other, an inclosing casing for each of said members, and means to simultaneously adjust said casings toward and 15 from one another, together with pipes to conduct the pulp into and out of said casings.

2. An engine of the type described for refining pulp comprising a shaft, two conical 20 members fixed thereon with their apices in contiguous relation one to the other, one of said members having a greater superficial area than the other, an inclosing casing for each of said members, means to simultaneously adjust said casings toward and from 25 one another, together with pipes to conduct the pulp into and out of said casings, and means to permit endwise play of said shaft 30 in its bearings within narrow limits.

3. An engine of the type described for refining pulp comprising a shaft, two conical 35 members fixed thereon with their apices in contiguous relation one to the other, an inclosing casing for each of said members, a single adjusting means engaging each casing to simultaneously move said casings toward and from one another, means to permit limited 40 endwise play of said shaft in its bearings, together with a supply-pipe leading into the intake end of one casing, and a pipe extending from the outlet end of said casing to the intake end of the second casing, and a suitable outlet pipe from the latter.

4. An engine of the type described for refining pulp comprising a shaft, two conical 45 members fixed thereon with their apices in contiguous relation one to the other, one of said members having a greater superficial 50 area than the other, an inclosing casing for each of said members, adjusting means to move said casings toward and from one another, means to permit limited endwise play of said shaft in its bearings, together with 55 a supply pipe leading into the intake end of

one casing, a pipe extending from the outlet end of said casing to the intake end of the second casing, and a suitable outlet pipe from the latter.

5. In a double pulp-refining engine, the 60 combination, of two slidably mounted casings of different size, a grinding member in each casing of different area, a shaft mounted for free endwise movement, to which the grinding members are secured, means to connect the casings together for simultaneous movement toward and from each other to vary the radial distance of the grinding members from the interior surface of the casings, a pipe to supply the pulp, to be 65 ground, to the interior of the larger casing, a pipe to conduct the pulp after the first grinding operation in the larger casing to the smaller casing, and a delivery pipe therefrom, whereby, by reason of the differences 70 in area of said grinding-members when the pulp is supplied to the casings, the grinding members and said shaft will automatically move in the direction of the axis of said shaft a distance proportionate to the 75 difference in area of said grinding members, and whereby the pulp in the larger casing will receive less harsh treatment than in the smaller casing.

6. In a double refining paper pulp engine, 80 the combination, of a common shaft mounted for free endwise movement, bearings in which the shaft is mounted, two conical-shaped grinding members of different areas secured to said shaft, slideable standards, 85 casings secured to the standards and inclosing the grinding members, a shaft provided with right and left hand threads to enter threaded openings in the standards to cause the casings to move toward and from each 90 other to vary the distance of the casings from the grinding members, means to supply the pulp to be ground, to the larger casing, a pipe leading from this casing to the other casing, and a discharge pipe from the 95 latter, whereby the difference in area of the two grinding members and the means to adjust the casings as described, the pulp will be subjected to a double refining process and the grinding members will be automatically positioned, as described.
